UNITED STATES PATENT OFFICE.

CARL F. BUSCHNER, OF NEW YORK, N. Y.

DESIGN FOR SKIRT-BINDING.

SPECIFICATION forming part of Design No. 31,109, dated June 27, 1899.

Application filed May 27, 1899. Serial No. 718,584. Term of patent 7 years.

To all whom it may concern:

Be it known that I, CARL F. BUSCHNER, a citizen of the United States, and a resident of New York city, New York, have invented and 5 produced a new and original Design for Skirt-Binding, of which the following is a specification, reference being had to the accompanying drawings, forming part thereof.

Figure 1 is a face view of a skirt-binding 10 showing my design, and Fig. 2 an enlarged cross-section thereof on line 2 2, Fig. 1.

The leading feature of the design consists 15 of a body having an upper and a lower stripe and a series of intervening rectangular figures arranged in a row.

a represents the body of the skirt-binding, and *b* is the brush. The body *a* is provided with the upper stripe *c*, the lower stripe *d*, and the series of intervening rectangular figures *e*.

What I claim is—

The design for a skirt-binding, substantially as herein shown and described.

Signed by me, at New York city, New York, this 26th day of May, 1899.

CARL F. BUSCHNER.
